CLAIM

The ornamental design for a humidifier base for low-flow oxygen therapy, as shown and described.

DESCRIPTION

FIG. 1 is an isometric view of a design for a humidifier base for low-flow oxygen therapy.

FIG. 2 is a front view of the design for the humidifier base. FIG. 3 is a rear view of the design for the humidifier base. FIG. 4 is a left-side view of the design for the humidifier base.

FIG. 5 is a right-side view of the design for the humidifier base.

FIG. 6 is a top view of the design for the humidifier base; and,

FIG. 7 is a bottom view of the design for the humidifier base. The broken lines illustrate portions of the humidifier base and form no part of the claimed design.

1 Claim, 5 Drawing Sheets
